(57) **CLAIM**

The ornamental design for a durable portable pressurized mist cooling device, as shown and described.

DESCRIPTION

FIG. 1 is a top left perspective view of the personal cooling apparatus showing the handle in its normal, retracted position.

FIG. 2 is a top right perspective view of the personal cooling apparatus showing the handle in its normal, retracted position.

FIG. 3 is a top view of the personal cooling apparatus.

FIG. 4 is a bottom view of the personal cooling apparatus; and,

FIG. 5 is the perspective view of FIG. 1 of the personal cooling apparatus, showing the handle in its extended position.

The nature and intended use of the article in which the design is embodied is as a personal cooling apparatus that contains a liquid and, when pressurized, ejects the liquid in a mist. The personal cooling apparatus is pressurized by pumping a handle in the top of the apparatus.
